US0D1105918S

(12) **United States Design Patent** (10) Patent No.: **US D1,105,918 S**
(45) Date of Patent: ** Dec. 16, 2025

(54) **BOTTLE**

(71) Applicant: **Target Brands, Inc.**, Minneapolis, MN (US)

(72) Inventors: **Richard P. Riedel**, Blaine, MN (US); **Casey M. Danyluk**, Minneapolis, MN (US); **Stacy L. Abel**, Champlin, MN (US); **Ryan P. McCoy**, Falcon Heights, MN (US); **Jessica M. Wilson**, Minneapolis, MN (US); **Michael M. Habig**, Cincinnati, OH (US); **Christine A. Nelson**, Palm Beach Gardens, FL (US); **Jason A. Edouard**, Maple Grove, MN (US); **Nicholas A. Cyr**, Santa Clarita, CA (US); **Nora K. Flood**, Chicago, IL (US)

(73) Assignee: **Target Brands, Inc.**, Minneapolis, MN (US)

(**) Term: **15 Years**

(21) Appl. No.: **29/875,289**

(22) Filed: **May 2, 2023**

(51) LOC (15) Cl. **09-01**

(52) U.S. Cl.

USPC **D9/549**

CLAIM

The ornamental design for a bottle as shown and described.

DESCRIPTION

FIG. 1 is a perspective view of a first embodiment of a bottle showing our new design;

FIG. 2 is a front view thereof, the back view being identical;

FIG. 3 is a right side view thereof, the left side view being identical;

FIG. 4 is a top view thereof;

FIG. 5 is a bottom view thereof;

FIG. 6 is a perspective view of a second embodiment thereof;

FIG. 7 is a front view of FIG. 6, the back view being identical;

FIG. 8 is a right side view of FIG. 6, the left side view being identical;

FIG. 9 is a top view of FIG. 6;

FIG. 10 is a bottom view of FIG. 6;

FIG. 11 is a perspective view of a third embodiment thereof;

FIG. 12 is a front view of FIG. 11, the back view being identical;

FIG. 13 is a right side view of FIG. 11, the left side view being identical;

FIG. 14 is a top view of FIG. 11;

FIG. 15 is a bottom view of FIG. 11;

FIG. 16 is a perspective view of a fourth embodiment thereof;

FIG. 17 is a front view of FIG. 16, the back view being identical;

FIG. 18 is a right side view of FIG. 16, the left side view being identical;

FIG. 19 is a top view of FIG. 16;

FIG. 20 is a bottom view of FIG. 16;

FIG. 21 is a perspective view of a fifth embodiment thereof;

FIG. 22 is a front view of FIG. 21, the back view being identical;

FIG. 23 is a right side view of FIG. 21, the left side view being identical;

FIG. 24 is a top view of FIG. 21;

FIG. 25 is a bottom view of FIG. 21;

FIG. 26 is a perspective view of a sixth embodiment thereof;

FIG. 27 is a front view of FIG. 26, the back view being identical;

FIG. 28 is a right side view of FIG. 26, the left side view being identical;

FIG. 29 is a top view of FIG. 26;

FIG. 30 is a bottom view of FIG. 26;

FIG. 31 is a perspective view of a seventh embodiment thereof;

FIG. 32 is a front view of FIG. 31, the back view being identical;

FIG. 33 is a right side view of FIG. 31, the left side view being identical;

FIG. 34 is a top view of FIG. 31;

FIG. 35 is a bottom view of FIG. 31;

FIG. 36 is a perspective view of an eighth embodiment thereof;

FIG. 37 is a front view of FIG. 36, the back view being identical;

FIG. 38 is a right side view of FIG. 36, the left side view being identical;

FIG. 39 is a top view of FIG. 36; and,

FIG. 40 is a bottom view of FIG. 36.

The broken lines shown in the drawings are included for purposes of illustrating portions of the bottle and form no part of the claimed design.
